US00D869637S

(12) United States Design Patent (10) Patent No.: US D869,637 S
(45) Date of Patent: * Dec. 10, 2019

(54) MASK FRAME FOR CPAP THERAPY

(71) Applicant: KONINKLIJKE PHILIPS N.V.,
Eindhoven (NL)

(72) Inventors: Eric Alan Higgins, Cheswick, PA (US);
Kevin Daniel Himes, Irwin, PA (US);
Jonathan Sayer Grashow, Cheswick,
PA (US); Elizabeth Eury, Latrobe, PA
(US)

(73) Assignee: KONINKLIJKE PHILIPS N.V.,
Eindhoven (NL)

() Term: 15 Years

(21) Appl. No.: 29/616,628

(22) Filed: Sep. 7, 2017

Related U.S. Application Data

(62) Division of application No. 35/500,815, filed on Oct.
9, 2015 (U.S. filing date under 35 U.S.C. 384), and having an international filing date of Oct. 9, 2015, now Pat. No. Des. 799,699.

(57) CLAIM

The ornamental design for a mask frame for CPAP therapy, as shown.

DESCRIPTION

FIG. 1 is a perspective view showing my design;
FIG. 2 is a front elevational view thereof;
FIG. 3 is a rear elevational view thereof;
FIG. 4 is a right side elevational view thereof;
FIG. 5 is a left side elevational view thereof;
FIG. 6 is a top plan view thereof; and,
FIG. 7 is a bottom plan view thereof.
The broken lines depict portions of the mask frame for CPAP therapy, that form no part of the claimed design.

1 Claim, 7 Drawing Sheets
